UNITED STATES PATENT OFFICE

139,477

DESIGN FOR A STOCKING

Louis Oseroff, Cleveland Heights, Ohio

Application August 23, 1944, Serial No. 114,977

Term of patent 14 years

(Cl. D47—7)

To all whom it may concern:

Be it known that I, Louis Oseroff, a citizen of the United States, residing in the city of Cleveland Heights, county of Cuyahoga, and State of Ohio, have invented a new, original, and ornamental Design for a Stocking, of which the following is a specification, reference being had to the accompanying drawing, forming a part thereof.

with parts shown in perspective, embodying my new design; and

Figure 2 is a fragmentary perspective view thereof, looking from the rear.

The top of the stocking is conventionally plain.

I claim:

The ornamental design for a stocking, substantially as shown and described.

LOUIS OSEROFF.
